Primary Examiner — Keli L Hill*Assistant Examiner* — Karra S Johnson(74) *Attorney, Agent, or Firm* — Indrajana Law Group, A Professional Law Corporation; Michael Indrajana, Esq.(57) **CLAIM**

The ornamental design for a portable speaker, as shown and described.

DESCRIPTION

FIG. 1 is a perspective view of a portable speaker incorporating the new design;

FIG. 2 is an alternate perspective view of a portable speaker incorporating the new design;

FIG. 3 is another alternate perspective view of a portable speaker incorporating the new design;

FIG. 4 is a front elevational view of a portable speaker incorporating the new design;

FIG. 5 is a rear elevational view of a portable speaker incorporating the new design;

FIG. 6 is a right elevational view of a portable speaker incorporating the new design;

FIG. 7 is a left elevational view of a portable speaker incorporating the new design;

FIG. 8 is a top plan view of a portable speaker incorporating the new design; and,

FIG. 9 is a bottom plan view of a portable speaker incorporating the new design.

The broken line showing of logos, button layouts and output configuration is included for the purpose of illustrating portions of the portable speaker and forms no part of the claimed design.

1 Claim, 9 Drawing Sheets(56)
